United States Patent Office.

F. FISCHBECK, OF CHICAGO, ILLINOIS.

Letters Patent No. 91,107, dated June 8, 1869.

IMPROVEMENT IN TRAVELLING-BAG FRAMES.

The Schedule referred to in these Letters Patent and making part of the same.

To all whom it may concern:

Be it known that I, F. FISCHBECK, of Chicago, in the county of Cook, and State of Illinois, have invented certain new and useful Improvements in Travelling-Bag Frames; and I do hereby declare that the following is a full, clear, and exact description thereof, reference being had to the accompanying drawing, making part of this specification, and to the letters of reference marked thereon, like letters indicating like parts wherever they occur.

To enable others skilled in the art to construct and use my invention, I will proceed to describe it.

My invention relates to travelling-bag frames; and consists in constructing and hinging the jaws in a novel manner, in connection or combination with metallic protectors.

In the drawings—

Figure 1 is a side view of my frame;

Figure 2 is a cross-section on the line $x-x$ of fig. 1, and also shows an inside end view of a part of the frame; and

Figure 3 is a cross-section on the line $y-y$ of fig. 1, and also shows an inside end view of a part of the frame.

In constructing my frame, I take a strip of metal, of suitable length and width, and bend it transversely, so as to form the rim A of the outer jaw of my frame, as clearly shown in fig. 1.

To the ends of this rim A, I connect, firmly, L-shaped metallic protectors B, provided, on their outer under side, with a boss or round projection, a, and also connect the protectors B, in like manner, to a metallic cross-strip, C, and in this way make a complete rigid metallic circuit for my frame.

Within the rim A, and so as to be on a line, or nearly so, with its outer edge, and at right angles with it, I place a metallic strip, D, suitably bent for the purpose, and connect it to the rim by means of small plates b, and so as to leave a narrow intervening space between.

The ends of the strip D, I bend at right angles to its length, so that the bent portion may be near to and parallel with the upper side of the protector B, and the length of the bent portion equal to the width of the protector, as clearly shown in fig. 2; and to these ends hinge the metallic strip E, made similar in size and shape to the strip D, and forming the inner jaw of the frame, the rim A and strip D forming the outer jaw.

Instead of bending the lower ends of the strip D, and hinging the jaw E to it, as shown in one side of fig. 1, and in fig. 2, the protector B may be provided with a but, c, and have the leaf d hinged to it, and then have the loose end of the leaf attached or riveted to the jaw E, as clearly shown on one side of fig. 1, and also in fig. 3.

The frame may be constructed with hinges like the one shown in fig. 2, or like the one shown in fig. 3, or with one of each kind, as shown in fig. 1.

It will be seen that a frame constructed in this way has a strong metallic rim, inside of which the lock can be fastened; has metallic protectors at the corners, serving to protect the hinges, and, if desired, forming a part of them, also protecting the bottom of the frame, and serving to connect the cross-strip C, to which the bag can be secured, thus forming a cheap, strong, useful, and durable frame.

Having thus described my invention,

What I claim, is—

1. A travelling-bag frame, having the rim A of the outer jaw, the protectors B, and the cross-strip E, constructed and arranged substantially as herein described, and for the purpose set forth.

2. Hinging the inner jaw E to the ends of the strip D, bent as herein shown and described, or to the protectors B, substantially as set forth.

F. FISCHBECK.
